UNITED STATES PATENT OFFICE.

IDA HAHN, OF PITTSBURG, PENNSYLVANIA.

DESIGN FOR A CARD-RACK.

No. 38,755.

Specification for Design.

Patented Jan. 12, 1909.

Application filed October 15, 1908. Serial No. 457,962. Term of patent 7 years.

To all whom it may concern:

Be it known that I, IDA HAHN, a citizen of the United States, residing at 2123 Waldon avenue, Brookline, Pittsburg, in the county of Allegheny and State of Pennsylvania, have invented a new, original, and ornamental Design for Card-Racks, of which the following is a specification, reference being had to the accompanying drawing, forming a part thereof.

The figure is a front elevation of a card rack illustrating my new design.

I claim:

The ornamental design for a card rack as shown.

IDA HAHN.
